PUMPING DEVICE IN PARTICULAR FOR
VOLATILE LIQUIDS

Paul André Guinard, Saint-Cloud, France

Application January 28, 1937, Serial No. 122,745
In France January 31, 1936

1 Claim. (Cl. 103—45)

The present invention relates to a pumping device particularly applicable to volatile liquids, such as gasoline, stored in underground reservoirs, the bottom of which may be below the level of the ground at a considerable depth which can attain 15 to 20 meters for large reservoirs. In this case, if it is desired to draw off the gasoline contained in such reservoirs by means of a pump, it is necessary to effect very considerable earthworks and masonry to arrange the pump at less than 4 meters above the bottom of the reservoir; effectively, for a suction height which is greater than 4 meters, the depression produced by the pump causes the gasoline to evaporate and the pump only sucks up vapour, so that by arranging the pump at a greater distance from the bottom of the reservoir, the latter cannot be emptied under satisfactory working conditions. Furthermore, the conditions of operation of such an installation are not satisfactory: when the level of the gasoline in the reservoir is low, for example when the suction height of the pump exceeds 2 meters, the evaporation begins to become considerable and the pump sucks up a mixture of liquid and vapour which produces extremely violent vibrations in the delivery pipe which are capable of destroying the welds between the suction pipe and the reservoir and of thereby causing flooding.

The device which is the object of the present invention is intended to overcome these drawbacks and it is characterized by the fact that it comprises a motor-pump unit immersed in the reservoir adjacent the bottom of the latter, and of which the pump, which is preferably of the centrifugal type, is directly coupled to a hydraulic motor actuated by a fluid which is not miscible with the liquid to be pumped and of which the density is greater than that of the latter, for example, in the case of a reservoir for gasoline, castor oil or glycerine.

By way of example, an embodiment of the device according to the invention has been described hereinafter and illustrated in the accompanying drawing.

Figure 1 is a diagrammatic elevation of the installation as a whole.

Figure 2 is an axial section of the pumping unit. The use of motor-pump units which are immersed in reservoirs to be emptied and which comprise a rotary pump coupled to a fluid motor, is known per se. However, the pure and simple application of such a device to the pumping of liquids such as gasoline is impossible in practice for the following reasons:

Owing to the difficulty in making the immersed machines perfectly liquid-tight, leakages of the actuating pressure-fluid occur in the reservoir and affect the purity of the liquid pumped, particularly in the case of considerable leakage. On the other hand, this same lack of liquid-tightness causes inlets of gasoline to occur in the casing of the hydraulic motor, particularly during the inoperative periods when the actuating fluid is not under pressure, said inlets of gasoline on the one hand preventing a satisfactory lubrication of the motor, which may cause seizing, and on the other hand modifying the actuating fluid which is used in closed circuit and which it becomes necessary to renew frequently.

The combination according to the present invention, of a pump immersed in the gasoline, with a motor actuated by a fluid which is not miscible with gasoline and is heavier than the latter, enables the problem to be completely solved.

1 is the underground gasoline reservoir (Figure 1) at the bottom of which is the pumping unit comprising a hydraulic motor 2 and the pump 3 arranged above a sump 4 provided in the bottom of the reservoir. The motor 2 is provided with an inlet pipe 5 and an outlet pipe 6 for the actuating fluid, of which the circulation is ensured by a hydraulic generator 7 actuated by a motor 8, the machines being arranged for example in a likewise underground room 9. The immersed pump 3 forces the gasoline into the pipe 10.

It will immediately be seen that the pump 3 always has a head, whatever be the level of the reservoir, so that it does not have to suck the gasoline but only to deliver it into the pipe 10, and that all the drawbacks due to the evaporation of the gasoline are therefore eliminated. As the pump does not have to suck, a centrifugal pump can be used (Figure 2) of which the rotor 11 is keyed on the shaft 12 carrying the rotor 13 of the hydraulic motor, for example a piston rotor, whereas the stator 3 of the pump is secured to the stator 2 of the motor. Between the two stators is interposed a chamber 14 which is filled with oil and which is separated from the said stators, by the stuffing and boxes 15, 16, through which the shaft 12 of the unit passes. Said shaft is supported by ball bearings 17, 17' lodged in the stator 2 of the hydraulic motor, and the rotor 11 of the pump, which is suspended on the end of the shaft 12, has no surface of friction with the stator 3, so that the gasoline which entirely fills the pump cannot cause any seizing of the latter.

The advantages of this device can be explained in the following manner:

As the height of the column of gasoline contained in the delivery pipe 10 is substantially equal to that of the column of actuating fluid contained in the pipes 5 and 6, but as the density of the actuating fluid is greater than that of the gasoline, the pressure which is exerted on the actuating fluid side of the stuffing box 16 is greater, even when the pump is inoperative, than that which is exerted on said stuffing box on the gasoline side, so that if there is defective liquid tightness, it is the actuating fluid which passes into the gasoline when the pump is inoperative, and as said fluid is not miscible with gasoline and is heavier than same, it falls to the bottom of the sump 4, so that such leakages entail practically no drawback. With regard to the leakages which normally occur during the operation of the unit, their volume is negligible as compared with the volume of gasoline delivered by the pump (for example 50 m.³ per hour), so that even if a portion of such leakages is carried along with the gasoline, the latter is only rendered impure to a quite-insignificant extent.

In the case in which the height of delivery of the gasoline is greater than the maximum height of the actuating fluid above the pump, for example when the end of the delivery pipe 10 is located above the ground as shown in Figure 1, the pressure of gasoline on the stuffing box 16 may become greater than that of the actuating fluid. To avoid this danger, the device according to the invention furthermore includes means for maintaining, when inoperative, the actuating fluid under a sufficient pressure to prevent the gasoline

from penetrating into the oil chamber 14. For this purpose, the return pipe 6 of the actuating fluid is connected to a bell 18 which is arranged for example in the room 9, and of which the upper part contains air which is compressed therein, during the operation of the installation, by a compressor 19 which is operated either manually, or preferably by the motor 8 which drives the generating pump 7. The level of the actuating fluid in the bell 18 can furthermore serve as a leakage indicator, a considerable drop in said level giving warning of the existence of a dangerous leakage of the actuating fluid. Of course, the air bell 18 can be replaced, without exceeding the scope of the invention, by any other pneumatic or hydraulic recuperating device.

I claim:

Pumping device, in particular for volatile liquids such as gasoline or the like stored in underground reservoirs, comprising a motor-pump unit which is immersed adjacent the bottom of the reservoir and which consists of a rotary pump and a hydraulic motor directly coupled to said pump, a motor-pump supply unit which is arranged outside the reservoir and of which the pump is connected to the hydraulic motor of the immersed unit by a closed circuit comprising a supply pipe and a return pipe, in said circuit a liquid which is not miscible with the liquid to be pumped and which is of greater density than the latter, an air bell, an air compressor driven by the motor of the supply unit, and means for connecting said air bell on the one hand to the return pipe of the closed supply circuit, and on the other hand to said compressor.

PAUL ANDRÉ GUINARD.
